UNITED STATES PATENT OFFICE.

ROBERT McKNIGHT, OF SARNIA, ONTARIO, CANADA.

TIME-CONTROLLED AUTOMATIC SWITCH.

1,173,448.

Specification of Letters Patent.

Patented Feb. 29, 1916.

Application filed June 19, 1913. Serial No. 774,692.

To all whom it may concern:

Be it known that I, ROBERT McKNIGHT, of the town of Sarnia, in the county of Lambton, in the Province of Ontario, 5 Canada, have invented certain new and useful Improvements in Time-Controlled Automatic Switches, of which the following is the specification.

My invention relates, to improvements in 10 time controlled automatic switches and the object of the invention is to devise a simple and cheap device which will automatically open and close a switch at any predetermined interval of time and it consists essentially 15 of a dial supported by and in frictional engagement with the hour hand driving sleeve and having twelve circumferential graduations corresponding to the twelve hours, a peripheral tripping cam connected 20 to the dial, a spring held switch operating lever co-acting therewith to throw the switch in one direction when the lever is freed, a stationary dial divided into twenty-four circumferential graduations, a rotatably 25 mounted peripheral cam, a pointer connected thereto and co-acting with the stationary dial and a driving connection between the rotating dial and the hour hand and the rotating pointer whereby the pointer and dial 30 are rotated in proportion of two to one and a spring held switch operating lever co-acting with the rotating dial for moving the switch in the opposite direction when the lever is freed as hereinafter more particularly 35 explained by the following specification.

Figure 1, is a general perspective view of a clock showing my device applied thereto. Fig. 2, is a perspective view of a clock mechanism, showing the front of the casing and 40 clock dial and hands removed. Fig. 3, is an enlarged perspective detail of the front plate of the clock and turning mechanism supported thereby. Fig. 4, is a sectional view 45 taken through the rotating cams. Fig. 5, is a detail front elevation of the rotating dial.

In the drawings like letters of reference indicate corresponding parts in each figure. 50 A is a clock casing, the bottom A' of which is preferably formed of insulating material.

A² is the front of the casing provided with the usual transparent face A³.

55 B is the clock mechanism of any usual form having the usual minute hand shaft

B' to which the minute hand B² is connected and the sleeve B³ mounted upon the minute shaft B' and to which the hour hand B⁴ is connected.

B⁵ is a pinion mounted on the minute shaft.

B⁶ is a gear secured to the hour hand sleeve B³, the gear B⁶ being driven from the pinion B⁵ by means of the gear B⁷ and 65 the pinion B⁸ mounted on the stud B⁹ and formed integral with the gear B⁷.

C is a dial mounted on the sleeve B³ sufficiently tight to rotate therewith when the sleeve is driven but free enough to be adjusted circumferentially by the hand of the operator. The outer periphery of the dial 70 C is provided with a knurled surface C'. The face of the dial is divided into twelve portions indicated by numerals circumferentially arranged around the outer edge of the dial from one to twelve.

D is a peripheral cam formed integral with the dial C so as to rotate therewith.

E is a gear mounted on a stud E' and 80 meshing with the gear pinion B⁸.

E² is a peripheral cam carried by the gear E being connected thereto by the sleeve E³ and frictionally held upon the hub of the gear E. The outer end of the sleeve is 85 provided with a squared end E⁴ and E⁵ is a pointer mounted upon the sleeve E³.

G is an ordinary clock dial provided with a central opening G' through which the dial C extends, and the opening G² through 90 which the end of the sleeve E³ extends so that the pointer E⁵ is to the outside of the clock dial. On the face of the clock dial is inscribed a supplemental dial G³ circumferentially divided from zero to twenty- 95 three.

H is a tilting switch provided with an operating arm H' and a knife end H³ co-acting with the spring fingers H⁴ secured in the insulating portion of the casing A'. 100

I is a spring held lever provided with an arm I' normally resting against the operating arm of the switch when the switch is in its closed position. The free end of the arm I rests against the periphery of the 105 cam C'.

J is a similar lever pivotally mounted at J' and having one end bearing upon the circumference of the cam E², the opposite end of the lever being designed to strike the 110 switch operating arm when the cam end of the lever is free.

In order to manually close the switch at any desired time I have provided a push button K.

Having described the principal parts involved in my invention I will briefly describe the operation of the same. When it is desired to open the switch at any predetermined time the dial C is rotated between the thumb and finger of the operator around the sleeve B³ of the hour hand. We will say for example, that the hour at which it is desired to open the switch is eight, the dial is then turned until the numeral eight is beneath the hour hand of the clock. By 15 this means the tripping point 3 of the circumferential cam C' is carried opposite the end of the spring finger I as the hour of the clock comes opposite the numeral eight of the clock. In order to automatically 20 close the switch at any predetermined time the number of hours intervening between the time for closing the switch and the time desired to re-open the switch is calculated and the pointer E⁵ is set opposite the numeral of the stationary dial G³ corresponding to such number of hours. We will take 25 for example, six o'clock p. m. as the time for again re-closing the switch and as the hour of eight o'clock, p. m. is the hour at 30 which the switch was opened it will be seen that there are twenty-two hours between the time of opening and the time of closing. The pointer E⁵ is, therefore, set opposite the numeral twenty-two of the dial G³.

35 As has been before described the gear wheel E and cam E² revolve once to every two revolutions of the dial C, therefore, the pointer E⁵ will travel one space, that is, from twenty-two to twenty-one and so on 40 during each revolution of the minute hand.

It will be understood that the notch or tripping point 4 of the cam E² will be opposite the tripping end of the lever J when the pointer is normally opposite the zero 45 point of the stationary dial. It will, therefore, be seen that when the pointer and cam are turned so as to point to the numeral 22 that the cam E² will have to revolve a distance to carry the pointer 22 spaces before 50 the tripping point of the cam comes opposite the tripping end of the lever J.

If it is desired to close the switch at any

other time than the time to which the mechanism has been set this may be done by forcing the button K upwardly so as to tilt 55 the switch in to the closed position.

From this description it will be seen that I have devised a very simple device whereby an electric switch may be opened and closed at any predetermined interval so that 60 the lights can be turned on and off as desired. This will be found particularly useful in turning on and off the lights of a show window of a store when it is desired to turn on the lights at a time after the 65 merchant has left the store and to turn them off again before he again reaches the store next morning.

By my device this may be automatically done. As my device is applied to an eight day clock it will be readily seen that when the device is once set to turn on and off the lights it will continue to do so automatically at the time required for the rest of the week.

75 What I claim as my invention is—

In a time controlled automatic switch, clock mechanism having the usual minute hand shaft and hour hand shaft, a switch provided with an operating arm, a pair of switch-operating spring held levers spring-held normally toward the operating arm of the switch and located at each side of such arm, a stud shaft carried by the clock mechanism, a gear mounted thereon, a train of gears 80 connecting the minute shaft with the gear carried by the stud shaft, a sleeve carried by the minute shaft, a pointer carried by the sleeve, a cam and dial frictionally held upon said sleeve, and with which one of the 85 levers coacts, there being gear connection between the sleeve and the train of gears connecting the minute shaft with the gear carried by the stud shaft, a cam frictionally mounted upon the hub of the gear mounted on the stud shaft and with which the upper 90 end of the other of the aforesaid lever members co-acts, a pointer mounted on the hub of the gear mounted on the stud shaft and a stationary dial co-acting with the pointer, 95 as and for the purpose specified.

ROBERT McKNIGHT.
